TELEPHONE SYSTEM

Walter Pinell, Falkensee, Germany, assignor to
 Siemens & Halske Aktiengesellschaft, Wern-
 erwerk, Siemensstadt, near Berlin, Germany

Application April 4, 1936, Serial No. 72,680
 In Germany May 7, 1935

10 Claims. (Cl. 179—18)

The present invention relates to automatically operated telephone systems.

In such systems it may be necessary, on account of the condition of the subscribers' lines, to equip the subscribers' stations differently, so that subscribers' stations whose lines are in a good condition are supplied with exchange battery feeding, while subscribers' stations having lines possessing a high resistance of leakages are 10 provided with local battery feeding.

The present invention aims at producing an arrangement which enables the variously equipped subscribers' stations to be connected to one and the same exchange, while at the same 15 time avoiding division of the subscribers' stations into groups in the exchange according to their mode of operation.

This is achieved in that switching means are automatically operated over selectors which are 20 set on lines leading to differently equipped subscribers' stations which either set up a microphone feeding bridge or merely a signalling circuit over the speaking leads according to the equipment of the subscribers' stations connected up.

The invention is represented in Fig. 1, parts 1 and 2, and modifications thereof are shown in Figs. 2 and 3 of the drawings, but the invention is not to be considered to be limited to these 30 embodiments. Only those details which are necessary for understanding the invention are represented. $Tn1$ represents a subscriber's station which possesses a magneto for initiating calls. The emission of impulses on the part of this subscriber's station is effected by operating a dial.

The subscriber $Tn2$ is provided with a station in which the initiation of a call takes place on removing the receiver. Impulse transmission takes place as before by operating a dial. As 40 indicated in the drawings both subscribers have access to the repeater $Ue1$ over the call finder AS. Switching over takes place in the repeater $Ue1$ in accordance with the equipment of the subscriber's station. Similar switching over 45 takes place in the repeater $Ue2$, this adjusting itself according to the equipment of the station of the desired subscriber.

When the subscriber at the station $Tn1$ initiates a call he operates his magneto In . Contact 50 3in is accordingly switched over so that the alternating current produced by the magneto takes the following path: earth, contact 4ab of a relay which is not shown, which is operated when all the call finders are engaged, winding I of relay 55 R, contact 5t, lead La, contact 2hu of the switch-

hook at the calling station, contact 3in, magneto In, lead Lb, contact 6t and earth. In circuit relay R energizes. Relay R operates its contacts and over contact 1r sets up the following locking circuit: earth, contact 4ab, winding I of relay R, contacts 1r and 8t, relay An, battery and earth. In this circuit the starting relay An is operated. Moreover, relay R on energizing prepares a testing circuit over contact 9r by connecting the winding II of relay R and the relay T to the contact bank of the call finder AS. Contact 10r is closed. By closing contact 12an earth is connected to the starting line an so that a free call finder is set in operation. If the call finder AS represented in the drawings is free the following 15 circuit is established: earth, contact 12an, lead An, contact 13v, relay C, battery and earth. Relay C operates and operates its contacts 14c and 15c. By means of contact 14c a testing circuit is set up for the call finder passing over the wiper sc. Contact 15c causes the energization 20 of the rotary magnet Das of the call finder AS. This energization takes place in the following circuit: earth, contacts 16p and 15c, rotary magnet Das, battery and earth. The rotary magnet advances the wipers of the call finder by one 25 step and operates the contact 17das. Relay C is short-circuited over contact 17das and releases. Accordingly, by this opening of contact 15c the rotary magnet of the call finder is de- 30 energized, contact 17das is opened whereupon relay C again energizes. This reciprocal play between the rotary magnet of the call finder and relay C continues until the calling line has been reached.

When the calling line is reached the following 35 testing circuit is established, earth, contact 14c, windings II and I of the testing relay P, wiper sc of the call finder AS, contact 9r, winding II of relay R, the contacts 10r and 18t which are arranged in parallel, relay T, battery and earth. In this circuit relays P and T energize. By the 40 energizing of relay P the stepping circuit of the rotary magnet Das is broken by the opening of contact 16p so that the magnet finally releases and relay C remains energized. The following 45 locking circuit is established over contact 19p: earth, contacts 20v1, 19p, winding I of relay P, wiper sc of the call finder AS. Over contact 21p relay U is connected to wiper sd of the call finder. 50 Relay U is, however, not energized since no potential is connected to the contact on which the call finder is set. The speaking leads are switched through at contacts 22p and 23p. Contact 24p causes relay V to energize, relay V energizes and 55

by switching over contact 13v causes the starting line An1 to be switched over on to the line An11, which leads to the call initiating relay of another call finder.

- 5 Through the energizing of relay T on the testing of call finder AS the starting relay An was deenergized by the opening of contact 8t unless another call is proceeding at the same moment from any one of the group of subscribers with 10 which relay An is associated in common. By the opening of contact 5t winding I of relay R is disconnected from the lead La. By the switching over of contact 6t the earth is disconnected from the lead Lb. Contact 18t is opened, but 15 this does not provoke any switching operations.

When the subscriber, after operating his magneto, takes up his receiver the switchhook contacts 1hu and 2hu are operated. Earth is hereby connected over contact 1hu through the impulse 20 contact nsi over windings I and II of the choke coil Dr to the two leads of the subscribers' lines. Two parallel circuits are thereby set up over the two leads of the subscribers' lines and the wipers of the call finder, these passing over winding I 25 of the transformer Tr2 to battery and earth. The transformer Tr2 forms an impulse repeater over which the impulses are inductively transmitted, and operate the polarized impulse receiving relay S arranged in series with the winding II of this transformer. The transformer Tr4 30 represents the speech repeater.

The closing of the two impulse circuits on taking up the receiver and after the call finder AS has been set causes the armature of the polarized 35 impulse receiving relay S to be switched over. Relay J is accordingly energized in the following circuit: earth, contacts 22v1, 23p, relay J, contact 24s. Relay J operates its contact 25j. This causes the energization of relay A. Relay A 40 operates its contacts 26a and 27a and 28a.

If, now, the subscriber operates his dial, the contact nsa is permanently closed during the operation of the dial while when the dial is allowed to run back the contact nsi is intermittently operated. On the first opening of contact nsi winding I of the transformer Tr2 is influenced over 45 both speaking leads simultaneously. The impulse receiving relay S accordingly moves its armature into the rest position. This causes the release of relay J. Relay J operates its contacts. Through contacts 25j relay V1 is energized. Relay V1 opens contacts 20v1 and 22v1. These do not, however, involve any switching operations 50 since the earth disconnected over contacts 20v1 and 22v1 is applied over contacts 27a and 28a on account of the energizing of relay A. On the closing of the parallel circuits by the dial contact nsi the impulse receiving relay takes up its working position once more. Relay J is accordingly 55 energized and switches over its contact 25j. The impulses transmitted in this way are used to set the final selector LW in the known manner.

When the impulse transmission is finished relay S remains in its operated position. Relay J accordingly also remains energized. Since contact 60 25j is switched over relay V1 is caused to deenergize. Contacts 20v1 and 22v1 accordingly return to normal.

If the desired line is free the testing relay P1 65 associated with the final selector energizes in the known way. This relay causes the switching through of the final selector and the transmission of ringing current in any known manner (with which the invention is not concerned). Assuming 70 that the called subscriber has a station which

is provided with magneto ringing and local battery feeding as is station Tn1 no switching over in the repeater Ue2 takes place.

The switching operations taking place at the station of the desired subscriber, whose station 5 is similar to Tn1, will now be explained. The ringing current transmitted to the called subscriber passes off the speaking lead Lan of the latter, the switchhook contact 2hu, the contact 3in of the magneto In in the rest position, over 10 the bell W and back over the lead Lbn. When the subscriber takes up his receiver the switchhook contacts 1hu and 2hu are operated so that earth is applied simultaneously over windings I and II over the choke coil Dr to the leads La and 15 Lb. Winding I of the transformer Tr3 in the final selector LW is accordingly influenced. Winding II is thus inductively influenced in such a manner that the relay E which is also a polarized relay is energized. This relay can be used 20 in any known manner to transmit metering impulses or to disconnect ringing current or to control any particular signals.

When the calling subscriber at station Tn1 replaces his receiver after setting up a call the contacts 1hu and 2hu are returned to normal. The earth, which is connected to the two speaking leads is thus disconnected. Relay S returns to normal and opens the circuit relay J at contact 24s. Relay J switches over contact 25j. This 30 causes relay A to deenergize, but relay V1, however, has previously energized. During the release period of relay A relay V1 is energized therefore. On the opening of contact 29v1 relay P accordingly deenergizes. Relay P operates its 35 contacts and finally breaks the testing circuit by opening contact 19p. Relay V releases and switches over contact 13v. When relay A falls back and V1 restores to normal the arrangement is again in the receiving condition.

The release of the final selector can take place in dependence upon the replacement of the receiver by the called party under the control of relay E or alternatively can be effected on the release of the call finder, in which case the permanent called condition existing at the called station must be rendered inoperative.

When the subscriber at the station Tn2 initiates a call the following circuit is set up on taking up the receiver: earth, contact 29t2, lead Lb1, loop 50 of the subscriber's station, lead La1, contact 30t2, winding II of relay R2, battery and earth. Relay R2 energizes and operates its contacts. Contact 31t2 is opened and contact 32r2 is switched over. The calling line is characterized in the call finder by contact 33r2. Contact 34r2 starts up a free call finder by applying earth to the starting lead An1 over contact 35t2. If the call finder AS is free the latter is started up by the aid of relay C in the same manner as has been described in 60 the case of the initiation of the call on the part of the subscriber at station Tn1. When the call finder AS reaches the line of the calling subscriber Tn2 the following testing circuit is set up: earth, contact 14c, windings II and I of relay P, wiper sc, contact 33r2, winding I of relay R2, contact 31t2, winding I of relay T2, battery and earth. The relays T2 and P energize. Relay P brings the call finder to rest in the manner already described. Relay T2 operates its contacts and 70 at contacts 35t2 disconnects the starting impulse from the starting lead An1. Contact 29t2 and 30t2 are switched over so that no leakage can occur from the speaking leads La1 and Lb1. Relay R2 is maintained energized over its winding I. 75

When the call finder AS is set on the line of the subscriber Tn2 the wiper *sd* of the call finder is connected to the earth potential Er. This causes relay U to be energized. Relay U effects 5 switching over in the repeater Ue1 in that by operating contact 40u earth is applied to the lead passing over wiper *sb* of the call finder. In addition the metallic connection between the two finders of the speech repeater Tr4 is broken by 10 contact 40u and replaced by the condenser Ko. Accordingly earth is connected to the speaking lead Lb1 and battery to the speaking lead La1 over winding I of the transformer Tr2. In the circuit the transformer receives an impulse on 15 switching through which causes the polarized relay S to energize. Relay S then causes relay J to energize in the manner already described. When the subscriber at the station Tn2 operates his dial the loop existing at the subscriber's station is interrupted. This affects the relay S in such a way that the latter changes its condition of energization at each opening and closing of the loop. In this way impulses are transmitted to 20 the final selector LW and effects the setting of the latter.

If the final selector LW is set on a subscriber's station which operates with the exchange battery feeding relay U1 in the final selector energizes. Relay U1 operates its contact 41u whereby a 25 similar switching over in the repeater Ue2 takes place as has already been described in the case of repeater Ue1.

It is, of course, also possible for a subscriber having exchange battery feeding to call a subscriber with local battery feeding and vice versa.

When on terminating the call the subscriber Tn2 replaces his receiver relay S returns to normal. Relay J and thereupon relays A and V1 de-energize. Relay P releases and promotes the release of relay U, so that the system represented may be taken into use again after relays R2 and T2 have released.

It may be mentioned that the construction of the subscriber's circuit at the calling station Tn2 also allows the final selector to be released directly 45 when the calling subscriber gives the clearing signal, in that, for example, the testing lead is opened at wiper *wc* of the final selector. In this case the incoming lead Lcn2 of the called subscriber is opened. This has the effect, since relay T2 is constructed as a slow-to-release relay, that relay R2 releases more quickly than does relay T2, so that the following circuit is established: earth, winding I of relay T2, contact 32r2, winding II of relay T2, contact 30t2, loop at the subscriber's station Tn2, contact 29t2, contact 31r2, and earth. In this circuit relay T2 holds up and by keeping open the contacts 35t2 and 37t2 prevents the establishment of the calling condition 50 at subscriber's line of station Tn2.

In Fig. 2 a further embodiment is represented, which enables one wiper at the call finder and at the final selector to be dispensed with. This figure represents how the controlling relays U and U1 can be operated over the testing wiper of the associated switching devices. The upper embodiment in Fig. 2 shows the wiper *sc* of the call finder AS over which, after the testing relay P has taken place and contact 45p has been closed, 55 relay U can be energized, so as to control the repeater Ue1. By specially adjusting the ratio of the resistance in the testing circuits which are reached over wiper *sc* the relay U may be caused to energize only when the call finder is set on the subscriber's lines for which switching over is

necessary. Relay U1, Fig. 2, is operated in a manner similar to that described above.

Fig. 3 shows the controlling arrangement for the switching over relay U1 involving a cam contact (*kop*) controlled by the final selector itself. 5 The contact is operated when the final selector is set on a line necessitating a switching over in the repeater.

What is claimed is:

1. In a telephone system, common-battery subscriber lines, local-battery subscriber lines, a link for interconnecting said lines for conversation, switching means for automatically connecting said link with any one of said lines where a call is initiated thereover, a common-battery current-supply connection and an alternative local-battery signalling connection in said link, and discriminating means in said link effective responsive to said connection of the calling line to said link and controlled through said switching means 10 according to the character of the calling line connected to the link for determining which of said connections is effective.

2. In a telephone system, loop-signalling subscriber lines, simplex-signalling subscriber lines, 25 a link for interconnecting said lines for conversation, switching means for connecting said link with a calling one of said lines, loop signalling connections in said link for enabling signalling to occur over loop-signalling lines, alternative 30 simplex-signalling connections in said link to enable signalling to occur over simplex-signalling lines, and discriminating means in said link controlled through said switching means according to character of the calling line connected to the 35 link for determining which of said connections shall be effective.

3. In a telephone system, subscriber lines having a given type of substation equipment, other subscriber lines having a different type of substation equipment, a connecting link common to all said lines and alternatively adaptable to cooperate with either class of substation equipment, switching means for automatically connecting said link to the line over which a call is initiated, 40 and adapting means in the link automatically controlled through the switching means responsive to said connection of said line thereto for adapting the link to cooperate with the connected substation equipment according to its type. 50

4. In a telephone system, subscriber lines divided into classes, a conversational link comprising two sections inductively associated for the interexchange of voice currents, each section having alternative feeding paths, each path 55 adapted for cooperation with a subscriber line of a different class, automatic switching apparatus controlled over a calling line of any class for connecting such line with the first section of said link, other switching apparatus controlled over 60 the calling line for connecting the other end of the link to a desired called line of any class, and means at said link controlled through the said connections made thereto for securing a feeding path at each section of the link adapted for 65 cooperating with the line connected to such section.

5. In an automatic telephone system, common-battery loop dialling subscribers' lines, local-battery simplex-dialling subscribers' lines, a link for 70 completing talking connections, means responsive to the initiation of a call over one of said lines for connecting said link with said calling line, a pair of circuits in said link, each adapted to cooperate with only one of said types of sub- 75

- scribers' lines, and means in said link for connecting to the calling line the circuit adapted to cooperate with the type of calling line connected to the link.
5. 6. In an automatic telephone system, common-battery loop-dialling subscribers' lines, local-battery simplex dialling subscribers' lines, a link for completing talking connections between any of said lines, means in said link controlled responsive to the connection of a calling line to said link for altering the calling end of the link circuit to correspond to the type of circuit of the calling line, and means in said link controlled responsive to the establishment of a connection with a called subscriber's line for altering the called end of the link circuit to correspond to the type of circuit of the called line.
- 10 7. In an automatic telephone system, subscribers' lines for substations having a given type of circuit, other subscribers' lines for substations having a different type of circuit, a link for completing talking connections between any of said lines, means in said link controlled responsive to the connection of a calling line to said link for adapting the calling end of the link circuit to cooperate with the type of circuit at the calling substation, and means in said link controlled responsive to the establishment of a connection with a called subscriber's line for adapting the called end of the link circuit to cooperate with the type of circuit at the called substation.
- 15 8. In a signalling system, an automatic switch, lines accessible to said switch, means for associating said switch with any one of said lines, signal receiving means in said switch, and discriminating means in said switch operated at times 5 to cause said signal receiving means to be controlled by signalling over one conductor of said line alone and operated at other times to cause said signal receiving means to be controlled by signalling over a plurality of conductors of said 10 line connected in parallel.
9. In a telephone system, an automatic switch, lines accessible to said switch over its wipers, means for causing said wipers to be associated with any one of said lines, a pair of alternative 15 signal receiving circuits in said switch, and discriminating means in said switch effective responsive to the association of said wipers with said line for determining which of said circuits shall be placed under the influence of said line.
- 20 10. In a telephone system, an automatic switch, lines accessible to said switch over its wipers, means for causing said wipers to be associated with any one of said lines, a pair of alternative 25 voice transmission circuits in said switch, and discriminating means in said switch effective responsive to the association of said wipers with said lines for determining which of said circuits shall be connected to said lines.
